Patented Sept. 23, 1958

183,580

COMBINATION INDOOR AND OUTDOOR SERVING TRAY

Ralph W. Seaford, Concord, N. C.

Application May 1, 1956, Serial No. 41,297

Term of patent 14 years

(Cl. D44—10)

FIG. 1

FIG. 3

FIG. 2

Figure 1 is a top perspective view of the combination indoor and outdoor serving tray;

Figure 2 is a perspective view looking from the bottom of the combination indoor and outdoor serving tray; and

Figure 3 is a side elevational view on a reduced scale of the combination indoor and outdoor serving tray.

I claim:

The ornamental design for a combination indoor and outdoor serving tray, substantially as shown.
